BANJO MUTE

Application filed May 31, 1928. Serial No. 281,877.

The object of this invention is to provide an attachment for banjos whereby the player of the instrument may soften the tone at will and thereby obtain musical effects which are not otherwise possible. More specifically stated, the invention seeks to provide a mute which is mounted within the sound box of the banjo and is operable by a knee lever mounted upon the rim of the banjo whereby the player by exerting pressure through his knee may cause the mute to bear against the vellum head of the instrument below the bridge and thereby dampen or soften the tone. The invention is illustrated in the accompanying drawings and will be hereinafter fully set forth.

In the drawings:

Figure 1 is a bottom plan view of so much of a banjo as is necessary for an understanding of our invention;

Fig. 2 is a transverse section on the line 2—2 of Fig. 1;

Fig. 3 is a detail section on the line 3—3 of Fig. 1;

Fig. 4 is a detail section on the line 4—4 of Fig. 3;

Fig. 5 is a section taken longitudinally of the knee lever and showing the manner of mounting the same upon the instrument, and

Fig. 6 is a detail perspective view showing the mounting of the mute.

In the drawings, the reference numeral 1 indicates the usual rim of a banjo sound box, 2 designates the vellum head which is stretched over the rim, 3 indicates the usual finger board and 4 designates the dowel bar which extends diametrically across the sound box and has its ends fitted in the rim with one end secured in or to the finger board.

The head 2 is stretched over the rim in the usual manner by the use of a clamping ring 5 and bolts 6 engaging over the edge of the ring and mounted in brackets or lugs 7 secured upon the rim. A bridge 8 is, of course, provided upon the head 2 and the banjo

strings are stretched over this bridge in the usual manner.

Extending across the dowel bar 4 is a supporting plate 9 which has one corner extended, as shown at 10, and then bent upwardly to form a fulcrum post or foot 11, as shown most clearly in Fig. 6. At its opposite side, this supporting or clamping plate 9 is formed with a depending lug 12 which is disposed at the side of the dowel bar and spaced therefrom and terminates in a lug 13 projecting inwardly in a plane below the dowel bar, as shown most clearly in Fig. 3. The main portion of this plate 9 is rectangular, as shown in Fig. 6, and it is provided with a number of openings 14 through which clamping screws 15 may be inserted, said screws being disposed at opposite sides of the dowel bar and passing through similar openings provided therefor in a lower clamping plate 16 which is disposed against the under side of the dowel bar. When the bolts or screws 15 are turned home, the plates 9 and 16 will be clamped to the bar in an obvious manner, and the lower clamping plate 16 is provided with recesses or notches, as at 17, in its side edges at the centers thereof to accommodate guide pins 18 which are fixed to and depend from the mute. One of these pins 18 is long enough to pass through the perforation or opening in the lug 13 and be always engaged therewith so that it serves as a constant guide for the mute and prevents the shifting of the mute out of its proper operative position. The guide pin at the opposite side of the guide is shorter and has a nut 19 mounted upon its lower end, a spring 20 being coiled around the pin between the said nut and the edge portion of the upper clamping or base plate 9 so that, when the mute has been pressed against the banjo head, this spring will be compressed and will aid in returning the mute to its normal inoperative position upon release of the actuating pressure. The mute is substantially a

metal plate bent upon itself to form an upstanding web 21 and a lower web 22 at a right angle to the upstanding web, the guide pins 18 being attached to and depending from the web 22, as will be readily understood. Secured to the front face of the upstanding web 21 of the mute is a cross bar of any durable light material, shown at 23, and upon the upper edge of this cross bar are pads 24 of cork, felt or other sound-deadening material. It will now be understood that reciprocation of the mute may be effected in a plane at a right angle to the plane of the banjo head so that the sound-deadening pads 15 may be pressed against the head immediately below the bridge and will thereby dampen or soften the tones produced by the player. To lift the mute into contact with the banjo head, there is provided a bell crank lever 25 which is fulcrumed at its angle upon the fulcrum foot or post 11, as shown at 26, said bell crank lever having the inner or free end of its longer arm connected with the mute by a pin and slot device, indicated at 27, whereby 20 the mute may be moved readily toward and from the banjo head without any bending or binding strain upon any of the working parts. The pendent arm of the bell crank lever is twisted upon itself so that it will 25 present its extremity to a connecting rod 28 in proper position to be engaged by the end of the pitman and be secured thereto by lock nuts 29. The connecting rod 28 is carried laterally from the bell crank through an 30 opening 30 provided therefor in the banjo rim and at its outer extremity is formed into or engaged with a bearing ball 31 seated in a socket member 32. A swinging retaining arm 33 is mounted upon an adjacent bolt 6 which forms one of the series of clamping bolts whereby the head is properly stretched, and this retaining arm fits around the end of the connecting rod and bears against the end of the socket member, as shown most clearly 40 in Fig. 5, a spiral coiled spring 34 being fitted about the end of the connecting rod between the banjo rim and the said retaining arm, as shown. The main operating lever 35 is preferably a sheet metal plate of such form that 45 it may rest against the knee of the performer when the banjo is held and supported in the usual playing position without causing any discomfort to the player. The knee lever is provided with lateral lugs 36 which are engaged with the same bolt 6 that supports the retaining arm 33 and is rotatable upon said bolt, the lugs being disposed respectively above and below said retaining arm so 50 that the proper relation of the parts will be maintained under all conditions. Beyond the lugs 36, the lever is formed with a stop finger 37 which is adapted to bear against the rim of the banjo and thereby prevent the free end of the lever being swung excessively 55 from the banjo under the influence of the

spring 34. A friction ball 38 is mounted in the outer end of the socket member 32, as shown clearly in Fig. 5, to bear against the inner side of the knee lever and thereby reduce frictional wear so that the lever will operate at all times without any binding. 70

Under the most usual playing conditions, the main operating or knee lever will be in the position shown in Figs. 1 and 5, the free end of the lever being spaced from the banjo rim and the mute being in its lowered position shown in Figs. 2, 3 and 4. If it should be desired to soften the tones of the instrument during a rendition, the player merely exerts pressure between his knee and the knee 75 lever so that the lever is rocked toward the banjo thereby exerting a push upon the connecting rod 28 which will be transmitted directly to the pendent arm of the bell crank lever 25 and said lever will be rocked so as to lift the mute into contact with the banjo head. Upon release of the pressure, the springs 20 and 34 will at once return the parts to the normal positions. All the parts of the device are very simple in construction and 80 may be produced from sheet metal so that the cost of production will be low and when the parts are assembled and applied the weight of the banjo will not be materially increased. The knee lever should have such 85 contour as to cover the expansion spring 34 to a sufficient degree to avoid unsightliness in the instrument and the lever may be ornamented in any desired manner. The mute member and the parts immediately associated therewith are all disposed within the sound box of the instrument so that they are 90 completely housed and will not be visible to an audience and will, consequently, not detract from the attractiveness of the instrument. 95 The lock nuts 29 positively connect the connecting rod with the bell crank lever and by adjusting these nuts longitudinally of the connecting rod the bell crank lever may be set so that the mute will normally lie at a 100 greater or a less distance from the banjo head and the player is thus enabled to adjust the device according to his own preferences or as his judgment may deem most apt to bring the desired effects. The terminal 105 of the bell crank lever may be provided with a plurality of openings therethrough so that the device may be placed within banjos having different depths of rim, it being understood that the connecting rod will pass 110 through the rim always at such a point as to avoid interference with any of the brackets which support the tension bolts or other parts 115 cooperating with said bolts. 120

Having thus described the invention, we 125 claim:

1. A mute attachment for banjos and similar instruments comprising a supporting structure secured upon the dowel bar of the banjo head, a mute mounted for reciproca- 130

- tion above said structure, guide pins depending from the mute through the supporting structure, an adjustable abutment mounted upon one of said pins, an expansion spring engaged with said pin between said abutment and the supporting structure, and means operable from the exterior of the banjo head for reciprocating the mute to and from the banjo head.
2. An attachment for banjos and similar instruments comprising a base plate, means for clamping said plate on the dowel bar of a banjo head, said plate being provided at one side with an upstanding fulcrum post, a mute mounted above the base plate, guiding elements depending from the mute through the base plate, a bell crank lever fulcrumed upon said post and operatively connected with the mute, and a main operating lever mounted externally upon the banjo rim and operatively connected with the bell crank lever.
3. A mute attachment for banjos and similar instruments comprising a mute body, sound-deadening elements carried by said body, a bell crank lever operatively connected with said body and pivotally mounted at one side of the same, a connecting rod connected with said bell crank lever and extending laterally therefrom through the rim of the banjo, a retaining arm mounted upon the rim of the banjo and engaged around the outer end of said connecting rod, an operating lever mounted upon rim of the banjo and arranged to press upon the end of the connecting rod, and an expansion spring disposed between the banjo rim and said retaining arm.
4. A mute attachment for banjos and similar instruments comprising a mute body, sound-deadening elements carried by said body, a bell crank lever mounted at one side of the body and operatively connected therewith, a rod connected with the bell crank lever and extending laterally therefrom through the rim of the banjo, a socket member engaged over the outer end of the rod, a retaining arm mounted for swinging movement upon the rim of the banjo and having its free end engaged around the rod and bearing against the socket member, an expansion spring disposed between the retaining arm and the banjo rim, and an operating lever mounted upon the rim of the banjo and extending over the outer end of said socket member.
5. A mute attachment for banjos and similar instruments comprising a mute body, sound-deadening elements carried by said body, a bell crank lever mounted at one side of the body and operatively connected therewith, a rod connected with the bell crank lever and extending laterally therefrom through the rim of the banjo, a socket member engaged over the outer end of the rod, a retaining arm mounted for swinging movement upon the rim of the banjo and hav-
- ing its free end engaged around the rod and bearing against the socket member, an expansion spring disposed between the retaining arm and the banjo rim, and an operating lever mounted upon the banjo rim and extending over the outer end of said socket member, said lever being provided at its fulcrumed end with a stop finger arranged to bear against the banjo rim.
- In testimony whereof we affix our signatures.
